UNITED STATES PATENT OFFICE.

WILLIAM F. GOODWIN, OF POWHATAN, OHIO.

IMPROVEMENT IN METALLIC SHIELDS FOR THE ARMY OR NAVY.

Specification forming part of Letters Patent No. 43,195, dated June 21, 1864.

To all whom it may concern:

Be it known that I, WILLIAM F. GOODWIN, of Powhatan, in the county of Belmont and State of Ohio, have invented a new and useful improvement in shields to be used in military or naval operations for the protection of men exposed to the fire of the enemy; and I hereby declare the following to be a full, clear, and exact description of the same, reference being had to the accompanying drawings, in which—

Figures 1 and 2 are side views of my improved shield adapted for army purposes, and showing it in position for use both as a shield and as a vehicle for the conveyance of baggage or ammunition, or for other uses. Figs. 3 and 4 are rear or front views of the same, showing the shield in the two positions indicated in Figs. 1 and 2.

My invention consists in the construction, arrangement, and operation of shields for army or navy purposes for the protection of men exposed to the enemy's fire, by the employment, whether as a fixed or movable attachment to ships or to any wheeled or otherwise supported frame, of metal plates curved so as to present its concave surface outwardly—*i. e.*, facing the enemy—substantially as hereinafter described.

To enable others to make and use my improvement, I shall now proceed to describe its construction and functions.

A in the drawings are plates made of steel, iron, or other material presenting requisite resistance to penetration of ordinary bullets or projectiles. These plates are curved to form a cylindrical surface—*i. e.*, concave on one side and convex upon the other.

The shield here shown is composed of plates—two in number—supported by or hung to a pair of wheels, B, by means of a frame-band, C, the ends of which are formed into axles, upon which the wheels are mounted.

E are supporting-legs, attached to the ends of the supporting-shaft by means of a jointed connection, F, so that the said legs may serve to elongate the shaft, thereby to accommodate, in case of necessity, a greater number of persons to draw or push the shields. The shields are secured to the shafts laterally by means of short braces G and vertically by means of the rods H, whose adjustable attachment I to and upon the shafts allows of the shields occupy-

ing either a vertical, horizontal, or inclined position in relation to the shafts.

The shields shown in the annexed drawings may be advantageously used in connection with a breech-loading cannon. For this purpose the two plates are perforated at their line of junction, the orifice being large enough to allow the barrel that passes through it of being properly directed or aimed. The breech-loading mechanism is in the rear of the plates—*i. e.*, on the convex side of the shield. At a given height the plates may have vertical or horizontal slots or perforations K, through which sharpshooters or gunners may fire their rifles. This shield, while affording protection to the men standing behind it and allowing them to advance or retreat at pleasure, has the additional property of rendering it exceedingly dangerous for the enemy to fire at it. The plates are calculated not only to prevent the balls from penetrating through them, but by reason of their concavity to deviate and repel all balls or projectiles that may be fired against them.

The shield, when mounted on wheels, and when not used in battle, may serve the purpose of a baggage-wagon or vehicle to carry the sick or exhausted soldier. For this purpose the brace-sockets I are loosened and allowed to slide along the shafts D until the rods H are parallel with or flat on their corresponding shafts, as shown in Figs. 2 and 3. When in this position, the sockets I are again fastened to the shaft, and the shield is thus securely held in a horizontal position, when it may be used as a wheeled vehicle for any purpose whatsoever.

The shields shown in the drawings are provided at the concave side thereof with spikes or spears M to prevent too near approach of the enemy.

Having thus described my invention, I would observe that I do not limit myself to the precise construction or arrangement of parts as hereinbefore described, this invention being susceptible of many modifications without departing from its principle.

What I claim is—

The construction, arrangement, and operation of shields for the purposes and in the manner described, the same consisting, essentially,

in the employment, whether as a fixed or movable attachment to ships or to any wheeled or otherwise supported frame, of metal plates curved so as to present their concave surface outwardly—*i. e.*, facing the enemy—substantially as herein set forth.

In testimony whereof I have signed my name

to this specification before two subscribing witnesses.

WM. F. GOODWIN.
